(57) **CLAIM**

The ornamental design for a stethoscope charm with attachment point, as shown and described.

DESCRIPTION

FIG. 1 is front view of the stethoscope charm with attachment point;

FIG. 2 is a back view thereof;

FIG. 3 is a right side view thereof;

FIG. 4 is a left side view thereof;

FIG. 5 is a top view thereof;

FIG. 6 is a bottom view thereof;

FIG. 7 is a top view of the stethoscope charm with attachment point in an alternate position; and,

FIG. 8 is a perspective view of a stethoscope with the stethoscope charm with attachment point in place thereon, with the stethoscope shown in dashed lines to indicate that it is for illustrative purposes only and forms no part of the claimed design.
